CLAIM

The ornamental design for a grass/leaf collection sheet, as shown and described.

DESCRIPTION

FIG. 1 is a perspective view of a grass/leaf collection sheet showing my new design;

FIG. 2 is a top plan view thereof, the bottom plan view being a mirror image of that shown;

FIG. 3 is a front elevational view thereof, the rear elevational view being a mirror image of that shown; and

FIG. 4 is a perspective view of the closed grass/leaf collection sheet.

FIG. 1

FIG. 2

FIG. 4

FIG. 3
